FILLING CAP AND STRAINER DEVICE

Abraham A. Arvintz, Brooklyn, N. Y., assignor to
 Seal-O-Strain Corporation, Brooklyn, N. Y., a
 corporation of New York

Application August 1, 1941, Serial No. 405,117

3 Claims. (Cl. 220—86)

This invention relates to devices for use in facilitating the transmission of fluid from one tank or compartment to another and for straining the fluid in its transmission. More particularly, the invention relates to devices of this type and kind designed for marine uses in the transmission of gasoline and similar fluids from tanks to the storage compartments of a vessel, and the object of the invention is to provide a device of the character described, employing a spring-seated control valve adapted to be automatically opened by the pressure of fluid introduced into the device in providing what might be termed a pressure actuated filling cap; a further object being to provide means keying the valve as well as the valve supporting casing against movement or displacement utilizing a lock controlling said keying means, said keying means and lock being all arranged within the structure of the valve casing, and with these and other objects in view the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my invention are designated by suitable reference characters in each of the views; and in which:

Fig. 1 is a sectional view through a filling cap made according to my invention, showing one adaptation thereof; and,

Fig. 2 is a side and partial sectional view showing another adaptation of the invention.

My improved filling cap is adapted primarily for marine uses where the same may be imbedded in the deck of a vessel or in the wall structure of a tank or compartment of the vessel, or on the other hand, incorporated in what is called a stand line or piping of the vessel. Further my improved cap is designed to be used where pressure of the fluid introduced through the cap serves to automatically open the valve of the cap, the valve being normally spring-seated. In devices of this type and kind I have also incorporated means for locking the valve in closed position while at the same time keying the valve supporting casing against displacement, thus preventing tampering with the filling device and ultimately with the fluid controlled thereby.

In Fig. 1 of the drawing is shown one adaptation of the invention, and in this figure 10 represents the casing of the device, the casing being substantially cup-shaped in form and is provided

at the bottom thereof with a large discharge 11 which is preferably threaded to receive a pipe or coupling in certain uses of the device, particularly in extending the device from a ship's deck to a tank or compartment arranged below the deck surface. The upper end portion of the casing 10 is enlarged as seen at 12, and terminates at its upper or outer end in a flange 13 seated in a groove 14 of a supporting wall or flooring 15 so that the upper surface 16 of the flange is flush with the upper surface 17 of the support. Any suitable fastenings may be employed to secure the casing to the support. In the construction shown, screws 18 are employed to enter a wooden support 15.

Where the casing 10 proper joins the enlargement 12 the casing has an inwardly protruding ring seat 19 upon which a valve-seat casing 20 rests and to which the same is secured by a number of screws 21, a gasket 22 being employed between the part 19 and the periphery of the valve casing 20.

The casing 20 has an upwardly extending internally and externally threaded sleeve portion 23 which forms a large admission passage 24 through the casing 20 into the casing 10. On the base of the sleeve portion 23 is a beveled valve seat 25 upon which a valve 26 seats. The valve 26 has a downwardly directed stem 27 which is freely supported in an open-work frame 28 having a top ring portion 29 which seats between the casing 20 and the part 19 of the casing 10, and centrally of the lower portion of the frame is a bearing 30 in which the stem 27 is freely moved. Between the bearing 30 and the valve 26 is a coil spring 31 which is arranged around the stem 27 and serves to normally support the valve on the seat 25 to resist predetermined pressures while at the same time providing automatic opening of the valve in pressure injection of fluid into the admission passage 24 through a pipe or tube coupled with the sleeve 23 after a closure plate 32 has been removed. The plate 32 seats upon a grooved portion 33 formed at the top of the casing 10 or in the flange portion 13 thereof, and this seating of the plate is sealed by a gasket 34. The plate 32 has a downwardly directed internally threaded sleeve portion 35 which engages the external threads of the sleeve 23. The plate 32 has centrally of the surface thereof, a countersunk key socket 36 whereby the key to fit this socket can be inserted to couple and uncouple the plate 32 as will be apparent.

Arranged upon the skeleton frame 28 and supported by this frame in the casing 10 is a large

screen or strainer 37 which is substantially cup-shaped in form and is disposed in spaced relation to the walls of the chamber 38 formed within the bottom portion of the casing 10.

The casing 20 in alignment with one of the screw receiving portions thereof is enlarged as seen at 39. This enlarged portion has a radial aperture 40 in which is mounted a key rod 41. The outer end portion of the rod 41 engages one side of the screw 21 to key this screw against rotation thus retaining the casing 20 against displacement from the casing 10. The outer end of the aperture 40 is plugged as seen at 42 in order to seal this aperture as will be apparent. The inner end of the rod 41 is provided with an aperture or eye 43 to receive an upwardly projecting pin 44 on the valve 26. The pin has above the rod 41 an aperture to receive a padlock or other lock element 45 which checks inward or opening movement of the valve 26 and also prevents displacement of the rod 41.

It will be understood however, that in the use of the device or when it is desired to pressure inject a fluid of any type or kind into and through the filling cap, the closure plate 32 is first removed, after which the lock 45 is removed by the use of a suitable key or otherwise. A pipe or coupling may then be connected with the sleeve 23 and fluid may be introduced under pressure into the chamber 24 unseating the valve 26 then passing out through the strainer 37 and into the chamber 38 and out through the discharge 11 or a pipe or tube coupled therewith.

When it is desired to remove the casing 20 for cleaning or replacing the strainer 37 or for making any alterations, repairs or replacement of the parts, this can be accomplished by first removing the lock 45, then manually or otherwise depressing the valve 26 to disengage the pin 44 from the rod 41, and then drawing the rod into the chamber 24 and removing the same through the open end of the chamber. This will free the casing 20 to permit its detachment by removing the screws 21 or where stud screws are employed, to simply remove the nuts 46 thereon.

The structure shown in Fig. 2 of the drawing differs from the structure shown in Fig. 1 basically in the form and contour of the main casing employed. In other words, substituted for the casing 10 is a casing 47 which instead of having the downward discharge 11 has a large discharge 48 at one side of the casing which is flanged as seen at 49 to be mounted on the flange 50 of a stand line or piping 51, a suitable gasket 52 being employed between the flanges 49 and 50 and bolts or screw devices 53 are employed to couple the parts. The only other difference in the two structures would be in providing a smaller flange 54 at the top of the casing 47 simply large enough to provide the groove seat 33 as in Fig. 1, upon which the closure plate 32 rests. In that the rest of the structure of Fig. 2 is identical with that shown in Fig. 1, no specific showing thereof is made, nor is this structure described. However in Fig. 2 part of the valve structure is indicated in dotted lines merely to illustrate the general similarity in arrangement.

It will be apparent that the cover or closure plate for the filling device has its outer surface flush with the corresponding surface of the casing and when the casing is imbedded in a support the entire device presents a surface in common alignment with that of the support. It will also

be apparent from a consideration of Fig. 1, that the closure plate serves to conceal the lock within the chamber 24 and further protect the lock from exposure to the elements.

Having fully described my invention, what I claim as new and desire to secure by Letters Patent, is:

1. A filling device of the class described, comprising a casing, the casing being open at the top, the bottom of the casing having a discharge opening, a member detachably supported in the upper portion of the casing and forming a valve seat, devices supporting said member in the casing, a valve engaging the seat of said member

10 to control admission of fluid into the casing, a cover plate detachable from said member, a projection on the upper portion of the valve, a key rod mounted in said member and keyed to one of said devices and to the projection on said valve 15 to retain said member against displacement from the casing, and a lock element on the projection of said valve outwardly of said rod to retain the valve in closed position to prevent unauthorized transmission of fluid through said casing.

2. A filling device of the class described, comprising a casing open through upper and lower end portions thereof, a spring-pressed and pressure-actuated valve controlling communication through said casing, an open-work frame sup-

30 porting and guiding said valve, a member detachable from the casing forming a seat in connection with which the valve operates, said member having an outwardly projecting internally and externally threaded sleeve portion, devices 35 coupling the member to said casing, a closure plate for the open upper end of the casing, said plate being detachable from said sleeve, the closure plate and said valve collectively forming a chamber within said sleeve, the valve having

40 a part extending into said chamber, a key rod mounted in said member, one end of the rod being keyed to said valve part, the other end of the rod being keyed to one of said devices in retaining said member against removal from the casing, and means engaging said valve part outwardly to said key rod and arranged within said chamber for retaining the valve in closed position to prevent unauthorized transmission of fluid through said casing.

3. A filling device of the class described, comprising a casing open through upper and lower end portions thereof, a spring-pressed and pressure-actuated valve controlling communication through said casing, an open-work frame sup-

55 porting and guiding said valve, a member detachable from the casing forming a seat in connection with which the valve operates, said member having an outwardly projecting internally and externally threaded sleeve portion, devices

60 coupling the member to said casing, a closure plate for the open upper end of the casing, said plate being detachable from said sleeve, the closure plate and said valve collectively forming a chamber within said sleeve, means keyed to one of said devices and to the valve retaining said member against displacement from the casing, and means on the valve and cooperating with said last named means retaining the valve in said member against unauthorized movement into

65 open position and controlling removal of said first named means in detaching the member from the casing.

ABRAHAM A. ARVINTZ.
